UNITED STATES PATENT OFFICE

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE

SHOE STRETCHER

Application filed October 14, 1926. Serial No. 141,640.

This invention relates to devices for use in stretching boots or shoes and is herein illustrated as embodied in a stretcher of similar character to that disclosed in United States Letters Patent No. 232,478, granted Sept. 21, 1880, upon application of F. A. Fay.

It is customary in shoe stretchers organized as set forth in said Letters Patent to provide an expansible forepart comprising a plurality of movable side sections and a toggle mechanism for imparting lateral movement to the side sections. The side sections are generally long enough to extend back 15 into the instep of the shoe, and there often is no heel part.

A so-called instep member is also often provided, as disclosed in the Letters Patent cited, lying above the expansible forepart and 20 movable upwardly for the purpose of exerting stretching pressure directly against the throat or the instep portion of the shoe in order to distribute and equalize the stretching pressure, it having been found that the mere 25 lateral separation of the forepart members may unduly stretch and even damage the throat of the shoe, at which locality its girth is least, irrespective of whether it is this part that it is desired to stretch.

In all such devices having instep members, so far as I am aware, the instep member has been pivotally secured at one extremity either to the members comprising the expansible forepart or to the mechanism for expanding the forepart, and its opposite extremity has been arranged to be engaged by the mechanism for pivotally raising and lowering the member. As a result thereof, the instep engaging member has always had the 40 same type of movement irrespective of the shape of the shoe being operated on; and frequently overstretched or tore one part of the shoe before some other part was stretched adequately, or at all.

The present invention corrects this difficulty by providing a shoe stretcher in which the instep-engaging member is mounted in such a manner that it is free to float or tilt about an axis located substantially centrally 50 of its length. Thus, the member may tilt

to adjust its position according to the shape of the instep portion which it engages, thereby accommodating itself readily to distribute the pressure evenly over the instep.

This and other features of the invention, including certain details of constructions and combinations of parts, will be described as embodied in illustrative devices and will be pointed out in the appended claims.

In the drawings, Fig. 1 is a view in side elevation showing one embodiment of the invention.

Fig. 2 is a plan view of the device shown in Fig. 1.

Fig. 3 is a perspective view of the device shown in Fig. 1 with the instep-engaging member and one of the side sections removed for the purpose of showing more clearly the expanding mechanism.

Fig. 4 is a detailed view of the device illustrated in Fig. 1 in side elevation and is designed to show the relative movements imparted to the various parts of the expanding mechanism upon actuation of the latter.

Fig. 5 is a detailed perspective view showing the under side of the instep-engaging member, and

Fig. 6 is a view in side elevation showing another embodiment of the invention.

Referring to the drawings, the expansible forepart of the illustrated shoe stretcher is indicated generally at 10 and comprises a plurality of side sections 12 pivoted together at their rear extremities by means of a hinge 14. The inner opposing faces 16 of the side sections 12 are, as illustrated, preferably flat and adapted to abut when the forepart is reduced to its narrowest width.

The inner flat faces of the side sections 12 are formed with cavities 18 (Fig. 3) for receiving a toggle mechanism comprising a block 20 to which are pivoted the inner extremities of a plurality of links 22 having their outer extremities pivotally secured to the side sections 12.

The toggle mechanism may be actuated to effect expansion or contraction of the forepart 10, by means including an operating member 24 which has screw-threaded engagement with a trunnion block 26. The inner flat faces

16 of the side members are recessed to accommodate the member 24, and pivotally to hold trunnions 28 carried by the trunnion block 26. Thus rotation of the member 24 in one direction imparts forward longitudinal movement to the toggle block 20, to cause spreading of the links 22 and separation of the side sections 12, whereas rotation of the member 24 in the reverse direction causes the block 20 to move rearwardly to draw in the links 22 and collapse the forepart 10.

10 The upper surface of the forepart 10 has a recess at 30. An instep-engaging member 32 is adapted to be seated within said recess 15 when the forepart member is collapsed, and is so shaped that when so seated its top surface forms a smooth continuation of the surface of the forepart member.

As shown in Fig. 5, the instep-engaging 20 block 32 is mounted for pivotal movement upon a pin 34 which extends laterally of the block substantially centrally of its length. The pin 34 is pivoted to corresponding extremities of a plurality of links 36, the other 25 extremities of which links are pivotally connected at 38 to the toggle block 20.

In the embodiment of the invention shown in Figs. 1 to 5, inclusive, the links 36 are secured to the block 20 immediately in the 30 rear of the toggle links 22. Thus it will be seen (Fig. 4) that when the toggle links 22 are spread apart they will engage the links 36 between their ends thereby imparting upward movement to the upper ends of the links 36 and consequently to the instep-engaging 35 block 32. On the other hand, when the links 22 are being drawn together, the block 32 is free to descend under gravity or pressure from the shoe upper into the recess formed in the forepart 10. It is also pointed out that as the forepart is expanded and the instep 40 engaging member is swung upwardly the toggle block 20 moves forwardly, and the disclosed construction is such that this forward 45 movement takes place faster than the component of pivotal movement of the instep-engaging member towards the rear of the forepart. Accordingly, upon expansion of the forepart, the instep block moves forwardly as well as upwardly relatively to the forepart, thus being pushed into the shoe and thereby readily accommodating itself to the contour thereof, since it will settle more readily into its natural position under the 50 considerable friction present, if it is acted on by stresses in various directions.

In the embodiment of the invention illustrated in Fig. 6, the links 36 are pivotally secured to a projection 40 formed on the upper 60 surface of the toggle block 20. In expanding the forepart of this embodiment of the invention, forward movement imparted to the toggle block 20 results in direct forward movement being imparted to the instep block 35 through the links 36, and the forward por-

tion of the recess 30 acts as a cam in imparting upward movement to the instep-engaging block 32.

In the embodiment shown in Figs. 1 to 5, the upward pivotal movement of the instep block about the axis 34 is entirely free, the instep block being pivotally supported only on the ends of the links 36 which rest against the toggle links. Thus the instep member is free to tilt or float about an axis located substantially centrally of its length. In the embodiment shown in Fig. 6 the pivotal movement is less free, but in any given adjustment of the member 24 a limited range of tilting movement of the instep member may be produced by unbalanced pressure of the shoe upper on its front or back portions. Thus in both cases, the block may tilt forwardly or rearwardly to adjust its position according to the shape of the instep portion of the shoe which it engages, and thus avoid undue stretching or damage at any one locality.

It should be noticed, also, that the instep block is mounted independently of the forepart, being carried solely by the forepart expanding means.

Having fully described my invention, what I claim as new and desire to secure by Letters Patent of the United States is:

1. A shoe stretcher, having, in combination, an expandible forepart having two separable sections, a member located between the sections and arranged to separate them, and an instep-engaging member mounted on said member.

2. A shoe stretcher, having in combination, an expandible forepart, means located at the ball portion of said forepart to expand said forepart, and an instep block carried solely by said means.

3. A device of the character described having, in combination, an expandible forepart having laterally separable sections, expanding mechanism located within said forepart and arranged to press said sections apart, and an instep-engaging member pivotally secured to said expanding mechanism.

4. In a shoe-stretching device, a forepart comprising a plurality of side sections, a toggle mechanism for imparting movement to said side sections, and an instep block pivotally secured to said toggle mechanism.

5. A shoe stretcher, having in combination, an expandible forepart, mechanism located in the ball portion of the forepart for expanding said forepart, and an instep-engaging member carried by said expanding mechanism, said mechanism being constructed and arranged to permit movement of the instep-engaging member relatively to said forepart upon expansion of the latter.

6. A device of the character described having, in combination, a forepart formed with a recess in its upper surface, an instep-en-

gaging block seated within said recess, means for connecting said instep-engaging block to the forepart comprising a member located in the ball portion of the forepart, and means 5 for actuating said member to lift the instep-engaging block.

7. In a shoe-stretching device, a plurality of pivotally mounted side sections having a recess formed in their upper surfaces, an 10 instep block mounted within said recess, and a toggle mechanism pivotally secured to each of said side sections and to the instep block and arranged to be actuated to cause separation between each of said side sections and 15 the instep block.

8. A device of the character described having, in combination, a forepart comprising a plurality of side sections, an expanding mechanism including a toggle block and a 20 plurality of links connecting the toggle block to said side sections, and an instep-engaging member, said links serving as cams for imparting movement to said instep-engaging member.

25 9. A device of the character described having, in combination, a forepart comprising a plurality of side sections, a toggle mechanism located between said side sections, an instep-engaging member seated within a recess formed in the upper surface of the forepart, and links connecting the instep-engaging member with the toggle mechanism in such a manner that movement imparted to the toggle mechanism results in movement 35 imparted to the instep-engaging member.

10. A device of the character described having, in combination, an expansible forepart, and an instep-engaging member mounted for tilting movement about an axis 40 located substantially centrally of the length of the instep-engaging member.

11. A shoe form comprising a plurality of side sections mounted for movement relatively to each other, and an instep-engaging 45 block mounted for free tilting movement about a laterally extending axis located substantially centrally of the length of the instep block.

12. A device of the character described 50 having, in combination, an expansible forepart formed with a recess in its upper surface, an elongated instep-engaging member located in said recess for tilting movement about an axis extending laterally of the instep-engaging member substantially centrally of the length thereof.

13. A device of the character described 55 having, in combination, an expansible forepart formed with a recess in its upper surface, an instep-engaging member located within said recess and pivotally connected to the expansible forepart member, and means 60 for varying the location of the pivotal axis of the instep-engaging member relatively to the forepart.

14. A shoe stretching device of the character described, having, in combination, an expansible forepart, a pivotally mounted instep-engaging member, and means for expanding said forepart, constructed and arranged to impart forward movement to said instep-engaging member relatively to said forepart, when operated to expand the forepart. 70

15. A shoe stretching device, having in combination, a member for engaging and applying pressure to the instep portion of a shoe, an expansible forepart, and a mechanism for expanding said forepart, the forepart acting as a cam to impart elevational 75 movement to said instep-engaging member, upon expansion of the forepart. 80

16. A shoe form comprising, in combination, a split forepart formed with a recess in the upper surface thereof, an instep member seated within said recess, and means to expand the forepart in such a manner that the forward part of the recess acts as a cam in imparting elevational movement to said instep member. 85

In testimony whereof I have signed my name to this specification.
